UNITED STATES PATENT OFFICE.

WILLIAM T. SMITH AND WILLIAM K. SMITH, OF PHILADELPHIA,
PENNSYLVANIA.

DESIGN FOR WOVEN FABRIC.

SPECIFICATION forming part of Design No. 24,064, dated February 26, 1895.

Application filed January 7, 1895. Serial No. 534,137. Term of patent 7 years.

To all whom it may concern:

Be it known that we, WILLIAM T. SMITH and WILLIAM K. SMITH, residing at Philadelphia, in the county of Philadelphia and State of Pennsylvania, have invented and produced a new and original Design for a Woven Fabric, of which the following is a specification, reference being had to the accompanying drawing.

10 The leading feature of our design is the representation of a lion's skin, shown on a contrasting ground, and having representations of scrolls at the sides and ends as shown in the accompanying drawing; which is sufficient

to enable others skilled in the art to make 15 and use our invention.

It is obvious the configurations may be woven in, or printed on the fabric.

Having as above fully described our invention, what we claim as new, and desire to secure by Letters Patent, is—

The design for a woven fabric, as shown in the accompanying drawing.

W. T. SMITH.
W. K. SMITH.
